TELEPHONE INSTRUMENT

Paul T. O'Neil, Englewood, N. J., assignor to Connecticut Telephone and Electric Corporation, Meriden, Conn., a corporation of Delaware

Application November 1, 1950, Serial No. 193,378

7 Claims. (Cl. 179—100)

1

This invention relates to a structural and functionally improved telephone instrument.

It is an object of the invention to provide a device of this character which may alternatively be supported from a wall or similar surface or may—in conventional manner—be disposed upon a horizontal surface such as a desk top, the instrument requiring no alteration or rearrangement on either one of such surfaces.

A further object is that of designing an instrument of this type which will include relatively few parts each individually rugged and simple in structure and capable of economical production; such parts being susceptible of ready assemblage to furnish a unitary instrument which will be compact and of pleasing appearance.

With these and other objects in mind, reference is had to the attached sheets of drawings illustrating practical embodiments of the invention and in which:

Fig. 1 is a plan view of the base portion;

Fig. 2 is a side elevation showing that base portion partly in section and with a hand set associated therewith;

Figs. 3 and 4 are views similar to Fig. 2 but with other portions of the base broken away to disclose underlying structures; and

Fig. 5 is a fragmentary sectional view showing an alternative form of structure which may be employed.

In these views the numeral 10 indicates the base of the instrument which may be in the form of a hollow casing enclosing the necessary operating mechanism. This may include the various contacts, contact springs providing the gang switch etc. With the exception of one switch assembly, which resiliently resists shifting, that mechanism has not been shown. Such assembly has been diagrammatically indicated in Fig. 2 under the reference numeral 11. Also shown in that figure are the structures extending from that assembly in accordance with present teachings.

Conveniently, the casing presents an inclined face portion 12 upon which there appears an annular outline 13 within which indicia 14 is disposed. The latter in accordance with conventional practice may include the usual subdivisions of numbers and letters arranged in groups corresponding to those appearing in a usual dial

2

type telephone. Within the outline or band 13 casing 10 preferably provides a well portion 15 as shown in Fig. 3. A dial 16 may be mounted in this well. That dial is preferably provided with finger openings 17 below the conventional indicia groups 18 are disposed. These groups will correspond to the adjacent groups 18. Accordingly, an operator may use either group in operating the dial. That dial will be connected to the conventional circuit controlling mechanism in any acceptable manner. It is to be noted, however, that the indicia are disposed in a manner preferably such that they may be read when the instrument is positioned so that its right hand edge, as in Fig. 1, either faces towards the user or else extends downwardly.

The base provides a cradle portion which may be recessed with respect to face 12. This cradle portion is defined by pairs of spaced arms 19 between which the casing is provided with a slot 20. Extending upwardly within this slot is a bar 21. Adjacent the upper or left hand end of the casing as viewed in Figs. 1 and 2, the latter is provided with a ledge or projecting portion 22 below which a recess 23 is furnished. A plunger 24 extends into this recess. The inner end of the plunger projects through an opening in the casing and may mount a rotatable anti-friction member or roller 25. Similarly, a plunger 26 may have its outer end connected to bar 21 and its inner end mounting an anti-friction unit should it be necessary to employ the latter. Within the casing and between the inner ends of these plungers is an operating cam 27 pivotally supported as at 28. This cam bears against, or is suitably connected with the gang switch 11 so that when the cam is shifted the contact springs of the switch will correspondingly shift.

Adjacent the opposite end of the base from 40 which plunger 24 extends, the casing is recessed as indicated at 29. A hand set 30 including at one end a receiver 31 and at the opposite end a transmitter 32 has these units extending adjacent the surfaces defining recesses 23 and 29. The overall length of the hand set and spacing of the receiver and transmitter units is such that the described disposition of the parts may occur even when the hand set is only casually placed in the cradle of the instrument. With the latter disposed upon a horizontal surface as in Fig. 2, it

is apparent that gravity will cause the hand set to bear against bar 21 with sufficient force to cause plunger 26 to shift cam 27 to the position shown in full lines in that figure. Under these circumstances the transmitter and receiver leads will disconnect incident to an opening or separation of certain of the spring arms of switch 11. Thus, it is apparent that an instrument is furnished which may be properly disposed upon a desk or other horizontal surface and used in a conventional manner.

That instrument may additionally be mounted upon a vertically extending surface. This will be primarily achieved by having a member extending from the vertical surface, project through an opening in the base plate of the casing (not shown). If a more permanent association or mounting is desired, then, of course, that base plate may be removed and screws or bolts may secure it and the supported casing from the vertical surface. In any event, so supported, it is apparent that the parts will assume the positions shown in Fig. 4.

In that view it will be noted that the receiver unit 31 has moved downwardly into supporting relationship with the surface of recess 23. Therefore, it has engaged plunger 24. Again, due to the weight of the hand set, that plunger will have been forced into retracted position to shift cam 27 as shown in full lines in Fig. 2. An accidental displacement of the hand set is virtually precluded due to the fact that it will bear against the projection 22. The latter will act somewhat on the order of a fulcrum around which the hand set may pivot to a slight degree. This will cause that hand set to swing inwardly as shown in Fig. 4 so that its parts will be neatly disposed, with the central portion lying properly within the cradle and the transmitter arranged adjacent the surfaces of recessed portion 29.

As is apparent under these circumstances, if an operator grasps the hand set, he may readily lift it away from the casing or base. With such lifting, plunger 23 will shift outwardly due to the spring pressure transmitted by switch assembly 11 through cam 27. Therefore, the switch and its associated mechanism will become operative to energize the parts of the dial mechanism and hand set. With such positioning of the parts, cam 27 will shift to the position indicated in dot and dash lines in Fig. 2. Therefore, plunger 26 as well as plunger 24 will be shifted outwardly.

To facilitate a grasping of the hand set regardless of whether the instrument is supported upon the horizontal or vertical surface, the recesses into which the transmitter and receiver of that hand set extend are continued through to the outer edge of the base. This is clearly evident in Figs. 1 and 2. It is also evident from these figures that when the instrument is upon a horizontal surface and the hand set is lifted, plunger 26 will be shifted upwardly which will result in the cam 27 assuming the dotted-line position again due to the urging of the assembly 11.

Under certain circumstances it may be found that the response to movement offered by the cam and plungers is such that the spring action of assembly 11 should be supplemented. In that event, a structure such as has been suggested in Fig. 5, may be employed. In that view the numeral 32 indicates the well portion corresponding to the slot 20. The bar has again been indicated by the numeral 21. Its plunger 33 may be somewhat reduced and extend into and

through the base of a recess 34. The latter is conveniently defined by a part integral with casing 10. Within this recess, a spring 35 is arranged. As is apparent, this spring will supplement the spring action of the assembly 11 to assure a projection of plunger 33 when the hand set is lifted from the cradle. A similar structure may be provided in association with plunger 24. It has been regarded as being unnecessary to illustrate this duplication. It is also apparent that other supplemental spring structures might be employed.

Thus, among others, the several objects in the invention as specifically aforesaid are achieved. Obviously, numerous changes in construction and rearrangements of the parts might be resorted to without departing from the spirit of the invention as defined by the claims.

I claim:

1. A telephone instrument including in combination a base, a cradle portion forming a part of said base to support a hand set, said base being formed with recessed surfaces beyond the ends of said cradle portion to accommodate the transmitter and receiver units of a hand set, a projecting portion forming a part of said base and interposed between the cradle portion and one of the recessed surfaces, to provide a fulcrum for the surface of that unit of a hand set which extends into the adjacent base recess and a switch-actuating member mounted by said base and extensible beyond said cradle portion to be engaged by said hand set.

2. A telephone instrument including in combination a base presenting side edges, a cradle portion forming a part of said base and disposed adjacent and parallel one of said side edges, said base being formed with recessed surfaces beyond the ends of said cradle portion to accommodate the transmitter and receiver units of a hand set mounted upon said cradle portion, said recessed surfaces continuing through to the adjacent side edge of said base, a switch-actuating member extending from said cradle portion and to be engaged by said hand set and a relatively raised dial-mounting surface interposed between said cradle portion and the side edge opposite to the one into which said recessed surfaces extend.

3. In a telephone instrument a base, a cradle portion forming a part of said base and to receive a hand set, said base being formed with a recess adjacent one end of that portion and both said cradle and recess being formed with openings through which switch-actuating plungers to be shifted by the weight of a hand set may extend.

4. A telephone instrument including the combination of a base, a cradle portion forming a part of said base to receive a hand set, a recessed surface also forming a part of said base and disposed adjacent said cradle portion, both said portion and surface being formed with openings and switch-actuating plungers extending through said openings.

5. A telephone instrument including the combination of a base, a cradle portion forming a part of said base to receive a hand set, a recessed surface also forming a part of said base and disposed adjacent said cradle portion, both said portion and surface being formed with openings, plungers extending through said openings and a rotatable cam within said base and connected to each of said plungers for operating a switch mechanism within said base.

6. A telephone instrument including a base, a cradle portion forming a part of said base and to receive a hand set, said base being formed with recesses beyond each end of said cradle portion and a relatively raised dial receiving surface forming a part of said base, said surface being disposed to one side of said cradle portion and extending above the same. 5

7. A telephone instrument including a base, a cradle portion forming a part of said base and to receive a hand set, said base being formed with recesses beyond each end of said cradle portion, a relatively raised dial receiving surface forming a part of said base and disposed to one side of said cradle portion to extend adjacent one side edge of said base and said recesses 10 15

extending from said dial surface through to the opposite side edge of said base.

PAUL T. O'NEIL.
